INVENTOR.
John T. Wood.

BY *John C. Higdon*
ATTORNEY.

UNITED STATES PATENT OFFICE.

JOHN T. WOOD, OF EAST ST. LOUIS, ILLINOIS.

WASHBOILER ATTACHMENT.

1,423,823.

Specification of Letters Patent. Patented July 25, 1923.

Application filed April 22, 1921. Serial No. 465,096.

To all whom it may concern:

Be it known that I, JOHN T. WOOD, a citizen of the United States, residing at East St. Louis, in the county of St. Clair, in the State of Illinois, have invented certain new and useful Improvements in Wash-boiler Attachments, of which the following is a specification containing a full, clear, and exact description, reference being had 10 to the accompanying drawings, forming a part hereof.

My invention consists in the novel construction and combination of parts herein-after particularly described and distinctly 15 claimed.

The object of my invention is to provide a cheap and simple automatic washer having perforated vertical tubes which can be placed in a common wash-boiler, and form 20 a false bottom therein, upon which the clothes will be supported and thoroughly washed by the steam and hot water that is circulated through them after being discharged through the holes in said vertical 25 tubes.

In the drawings,

Fig. 1 is a top plan-view of my improved washer, and

Fig. 2 is a vertical section of the same 30 in operating position in a wash-boiler.

The numeral 1 designates the portable false-bottom member of my invention, which is somewhat rectangular and smaller than the bottom 2 of the wash-boiler 3, and 35 is provided with a straight downwardly-extending marginal flange 4 which rests upon the said boiler bottom 2 and removably supports the horizontal body 1 about one inch above the fixed bottom 2.

40 The adjacent ends of said downwardly-extending flanges 4 are cut away so as to provide a V-shaped water-inlet opening 5 between said ends at each corner of the said rectangular bottom-member, for permitting the water to enter thereat beneath 45 said false-bottom member 1, said flanges being slightly inclined (or spread) outwardly from said member 1 to the lower edges of said flanges.

50 Rising from the said rectangular bottom-member 1 are a series of vertical tubes 6 having numerous perforations 7 at various points in their length.

The upper ends of said tubes 6 are closed 55 by a suitable top-plate 8, but their lower

ends are open and in free communication with the steam-space 9 beneath said rectangular bottom-member 1.

The lower ends of said tubes 6 are firmly secured by means of solder or other fastening means to the said body-member 1, and they are each strongly braced by means of a heavy body of cast-iron or other metal 10 which surrounds their lower portions, and is soldered or otherwise fastened thereto, 65 and also to the underlying rectangular body-member 1.

Said heavy bracing-bodies 10 also act as weights, to hold the rectangular body-member down, during operation of the device, 70 and prevent the steam that is generated beneath said rectangular body-member from raising same too high above the wash-boiler bottom 2.

In operation, the clothes to be washed are 75 placed in the wash-boiler 3, above the said rectangular body-member 1, and surrounding the said vertical tubes 6, and boiled with soap until properly cleansed.

The steam beneath said body-member 1 80 will rapidly force boiling-water and steam up through said tubes 6, and discharge the same into and through the clothes, and thence the water will return to the steam-space 9 through said V-shaped openings between the ends of said flanges 4 of said rectangular bottom-member, and so on, as long as the water boils, and until the cleaned 85 clothes are removed from the boiler.

I claim:

A wash-boiler attachment, composed of a rectangular false-bottom member having a series of vertical perforated tubes rising from its upper surface, and provided with straight downwardly-extending outwardly-flared marginal flanges between the adjacent ends of which at each corner of said member are V-shaped water-inlet openings; and combined weights and braces surrounding the lower portions of said tubes and securely fastened to the said rectangular false-bottom member.

In testimony whereof, I have signed my name to this specification in presence of two subscribing witnesses.

JOHN T. WOOD.

Witnesses:

JOHN C. HIGDON,
HENRY L. HIGDON.
